UNITED STATES PATENT OFFICE

JAMES L. SUTTON, OF LOS GATOS, CALIFORNIA

BUILDING BLOCK

Application filed June 7, 1927. Serial No. 197,064.

This invention relates generally to molded blocks for use in building construction.

It has become common practice to construct the walls of buildings from precast

5 blocks of fire clay, concrete, or other suitable material. These blocks are generally molded in such a manner as to provide a hollow wall construction, and are provided with interfitting portions or other suitable means 10 for retaining the same in interlocking relationship. In all modern buildings, the walls are wired with electric lighting conductors, and the Fire Underwriters generally require that these conductors be strung through 15 metallic pipes or conduits. The arranging of metallic conduits and the necessary metallic outlet boxes in a wall constructed of hollow blocks or tile, is generally a difficult and expensive job even though apertures are provided in the blocks before the wall is assembled.

It is an object of this invention to devise a premolded building block for the construction of walls, which will make unnecessary 25 the positioning of wiring conduits after the wall has been constructed.

It is a further object of this invention to devise a premolded building block having an outlet box which is molded in the same, so 30 as to make it unnecessary to locate such a box after the wall has been assembled.

It is a further object of this invention to provide for metallic conduits in a wall constructed of a plurality of premolded blocks, 35 by forming the conduit of a plurality of sections, each section being molded within its associated block.

It is a further object of this invention to devise premolded building blocks or tiles 40 which will permit any system of conduits for electrical wires, without necessitating insertion of the conduits after the wall has been constructed.

Further objects of this invention will appear 45 from the following description in which I have set forth the preferred embodiment of my invention. It is to be understood that the appended claims are to be accorded a range of equivalents consistent with the state 50 of the prior art.

Referring to the drawings:

Figure 1 is a side elevational view illustrating a portion of a wall constructed of blocks incorporating this invention.

Fig. 2 is a detail illustrating how the 55 blocks of this invention are coupled together.

Fig. 3 is a perspective view of a building block having an outlet box cast within the same.

Fig. 4 is a perspective view of a building 60 block showing an outlet box cast within the same, the sectional conduit lengths connecting with the box being in the form of a T.

Fig. 5 is a cross sectional view taken thru an outlet box being employed as a switch 65 housing.

This invention may be outlined briefly as comprising a premolded building block within which is molded as an integral part thereof, a portion of a metal conduit. In constructing a wall, a certain number of blocks carrying these integral conduit sections are assembled so that the sections are alined to form a continuous passage for stringing electric light conductors. Where it is desired to extend an electrical connection thru the wall to provide for attachment of a light fixture, switch, or terminal connector, or where it is desired to join electrical wires in making abrupt bends, this invention makes use of a 70 block within which is premolded a suitable metal outlet box which communicates with the conduit sections. Instead of forming all of the blocks of a thickness equal to the depth of the wall being formed, certain of the blocks are intended to be set up in pairs, and have hollow inner faces. These relatively flat 75 blocks are retained together at their edges by means of suitable tie blocks.

Thus referring to the specific construction 80 which I have shown in the drawings, Fig. 1 illustrates a wall which has been fabricated from blocks constructed in accordance with this invention. These blocks are disposed in horizontal rows, each row having tie blocks 85 10 which are interconnected by pairs of blocks 11. The tie blocks 10 are of a thickness equal to the depth of the wall being formed and are of hollow construction, being provided with the openings 12 extending vertically there- 90 100

through. In order to provide for lightness, the inner faces of blocks 11 are hollowed out as indicated at 13, a central vertical rib 14 being formed to provide adequate compressional strength. The blocks are all retained together along adjacent edges, by suitable tongue and groove connections. For example the tie block 10 in Fig. 3 has been shown as provided with tongues 16 projecting from one edge thereof, and with grooves 17 upon the other three edges. The blocks 11 are each shown as provided with tongues 18 projecting from three edges thereof and a groove 19 formed along the third edge.

15 In assembling the wall the groove at the ends of block 11 are engaged with the grooves 17 of blocks 10, and the tongues along the top edge of blocks 11 are therefore aligned with the tongues 16 of tie blocks 10. The grooves 20 provided along the bottom edges of the next higher row of blocks, therefore fit over the projecting tongues 16 of tie blocks 10 and the tongues 18 along the upper edge of blocks 11. The tie blocks of alternate horizontal rows are 25 offset laterally or staggered. In other words a tie block of one horizontal row is aligned vertically with the central portions of blocks 11 of the next lower and next higher row of blocks. Therefore the central web 21 of each 30 block 10 is aligned vertically with the ribs 14 of blocks 11 so as to form continuous vertical columns for carrying compressional stresses. Cement grouting or suitable mortar is employed between the blocks to fill up the spaces 35 between the tongues and grooves and to secure the blocks together.

In practically all walls of this type, it is necessary to string electrical light conductors through the blocks. In my invention, instead 40 of inserting metal conduit pipe after the wall has been built, I provide certain of the blocks with integral conduit sections which are cast within the blocks during manufacture of the same, and these sections are assembled so as 45 to form continuous passageways for electric light conductors. For example I have shown certain of the tie blocks 101 provided with conduit sections 23 extending through the same and having its ends terminating adjacent the edges of the block. This conduit 50 section is cast within the block during manufacture and therefore is an integral part of the same. Likewise certain of the blocks 111 have conduit sections 24 molded within the 55 same, the sections being similar to sections 23 provided in the blocks 101.

As the conduit within the wall must make right angle turns in order to distribute the conductors to the desired points, certain of 60 the blocks are provided with cast in conduit sections which meet in the form of an L, while others may be provided with conduits meeting in the form of a T. When two conduit sections meet at an angle within a block, it is 65 preferable to provide an outlet box at the

junction point, so that the conductors may be conveniently connected together at such points. For example, tie blocks 102 have been shown as provided with conduits arranged to form an L junction, and a metal outlet box 26 of conventional construction is molded into the block to form an integral part of the same. The conduit sections 241 and 242 are likewise imbedded in the block 102, and are secured to the outlet box 26 in the usual manner. In Fig. 4 I have shown one of the flat blocks which is numbered 111, as being provided with a similar outlet box 26 to which are connected the conduit sections 243 and 244, to form a T-shaped junction.

The outlet boxes 26 shown in the blocks of Figs. 3 and 4 may be employed for the attachment of switches, or other electrical devices, in addition to their use as a means for making connections between the light conductors. However where the conductors terminate at an electrical instrument, an outlet box may be provided with a single conduit section. For example in Fig. 5 I have shown one of the tie blocks 103, as provided with a 90 molded in outlet box 27 and a single pipe section 28. A switch 29 has been shown as disposed within the outlet box 27, the switch having a front plate 31 flush with the wall plastering or covering 32. In Fig. 1 the outlet box of another tie block has been shown as providing a mounting for a light bracket or fixture 33. Likewise a block 113 has been shown as having an electrical connection terminal 34 mounted upon its outlet box.

In practice the wall is assembled in such a manner as to have conduit sections extending to the points where it is desired to have light fixtures, switches or other electrical devices. The pipe sections preferably have interfitting 105 ends in order to facilitate their alignment. For example certain sections may be provided with projecting ends 36 of reduced diameter to interfit with the ends 37 of other sections having an enlarged internal diameter. Set screws 38 may be provided so that when the blocks have been assembled, tightening of these set screws serves to electrically 110 connect all of the conduit sections, so that they may all be connected to a common ground. After the blocks have been assembled, and before the wall has been plastered or covered with wall board, the electrical conductors are strung through the conduit sections as by means of a steel tape or 115 other means commonly used by electricians. Covers are then secured to the outlet boxes which are not being utilized for mounting electrical devices, and the wall may then be plastered. In the specific arrangement of 120 conduit sections shown in Fig. 1, the electrical conductors enter the conduit system at point 41, and supply current to the terminal conductor 34 and to the electrical light fixture 33 which is controlled by switch 29. It is 125 130

obvious however that any system of conduit may be formed depending upon the manner in which the conduit carrying blocks are assembled.

5 I claim:

1. In a building wall consisting of a plurality of individual blocks, a series of adjacent blocks, each of the series having a section of metallic conduit embedded therein 10 with ends terminating substantially in different edges of the respective blocks in position to aline with the ends of conduit sections of adjacent blocks of the series, whereby a continuous metallic conduit is provided in 15 the wall for accommodating electrical wiring.
2. In a building wall, a plurality of individual blocks adapted to be assembled in series relationship to form a part of a wall, 20 one of said individual blocks having a metallic outlet box embedded therein and a conduit section extending to one edge of one of said blocks and communicating with said box, both said conduit section and said box 25 being embedded in said one block, said conduit section being adapted to communicate with conduit in the other blocks of said series for enabling extension of wiring thru the same to said box.
3. In a building wall, a plurality of individual blocks adapted to be assembled in series relationship to form a part of said wall, each of said individual blocks having a section of metallic wiring conduit em- 35 bedded therein with ends terminating substantially in different edges of the respective blocks in position to aline with the ends of conduit sections of adjacent blocks of the series when said blocks are assembled together 40 whereby a continuous metallic conduit for electrical wiring is provided in the wall, one of said blocks including a metallic outlet box in communication with the conduit section for said one block.
4. In a fabricated building wall, a series of blocks adapted to be assembled to form a part of said wall, said series including two blocks each having a hollowed inner face, a tie block engaging corresponding edges of 45 said first mentioned blocks, an outlet box embedded in said tie block, a conduit section extending from said box, and a conduit section embedded in one of said first mentioned blocks and adapted to aline with said first 50 named conduit section to form a passageway for electrical wires.

In testimony whereof, I have hereunto set my hand.

JAMES L. SUTTON.
